UNITED STATES PATENT OFFICE.

FREDERICK J. ENGLE, OF SOUTH OMAHA, NEBRASKA.

ATTACHING MEANS FOR BAILS.

No. 914,135.

Specification of Letters Patent.

Patented March 2, 1908.

Application filed May 26, 1906. Serial No. 435,052.

To all whom it may concern:

Be it known that I, FREDERICK J. ENGLE, a citizen of the United States, residing at South Omaha, in the county of Douglas and State of Nebraska, have invented new and useful Improvements in Attaching Means for Bails, of which the following is a specification.

This invention relates to a bail attaching means for metallic vessels, and the primary object of the same is to provide a simple and effective means for connecting the extremities of a bail to the body of a metallic vessel without cutting or perforating said body and by the use of a minimum amount of solder, thereby avoiding the formation of leaking joints at the points where the bail is attached to the vessel and materially reducing the cost of attaching the bail extremities.

The invention preferably consists of a vessel body having annular seats formed in the body and surrounded by circular beads to receive hollow caps in which the extremities of the bail are movably inserted, the maximum diameter of the caps being approximately the same as the diameter of the seats, and when the caps are applied solder receiving grooves are formed between the same and the beads surrounding the seats. The seats and beads may be formed by simple means at the time the body blank is cut and the body afterwards rolled into shape and completed in the ordinary manner. The seats will thus be accurately positioned at opposite points with relation to the body with material conveniences and advantages in assembling the caps and bail extremities in an expeditious and effective manner.

In the drawing: Figure 1 is a perspective view showing a metallic vessel, a bail, and bail engaging caps in dissociated relation. Fig. 2 is a transverse vertical section through a portion of the body of the vessel and one of the caps, the latter being shown detached. Fig. 3 is a view similar to Fig. 2 showing the cap applied to the seat and a portion or one extremity of the bail in engagement with the cap. Fig. 4 is a side elevation of a portion of the vessel body showing the bail attaching means in front elevation and also illustrating the bail in applied position.

Similar characters of reference are employed to indicate corresponding parts in the several views.

The numeral 1 designates the body of a metallic vessel similar to that ordinarily employed for holding and vending lard or analogous material. This body is formed of sheet metal and rolled into shape by suitable mechanism. The improvement consists in an advantageous form of bail attaching means, as hereinbefore indicated, and in providing diametrically opposite portions of the body 1 with seats 2 surrounded by beads 3, the seats being preferably of circular form and the beads having a corresponding contour. The seats 2 and beads 3 are constructed without perforating or cutting the metal of the body by the use of suitable dies or stamping devices, the said seats being preferably formed at the time the body blank is cut so that when the body is shaped and completed the seats will occupy proper relative positions in accurate distances from the upper edge or rim of the body to facilitate application of the bail extremities without requiring measurement or calculation and insure a balancing of the vessel by the bail when the latter is attached. Applied to each seat is a hollow cap 4 which is shown as of semispherical form, though other shapes or contours may be adopted. The cap 4 is formed with a central opening 5 for the reception of the angular end 6 of the bail 7, as clearly shown by Fig. 3. The maximum diameter of each cap is approximately the same as the diameter of the seat, and the inner wall 8 at least of the head 3 is inclined away from the adjacent portion of the cap when the latter is applied to the seat and thereby an outwardly diverged solder receiving channel or groove 9 is produced.

The caps 4 engaged by the angularly bent ends 6 of the bail 7 are applied to the seats as shown by Fig. 3 and the solder is run into the channels or grooves 9 forming an outwardly diverged solder filling in each seat as at 10, thus providing for a minimized use of solder and effectively resisting accidental disengagement of the caps and bail ends by reason of the gradual increase in thickness of the solder filling towards the outer surface of the latter and thus setting up a wedging action or a wedge-shaped securing key means having an annular relation to each cap.

In addition to the convenience, expeditious and manufacturing economy characterizing the improved bail attaching means

hereinbefore explained, a durable association of the bail with relation to the vessel body results, and leakage of the contents of the vessel cannot ensue in view of the imperforate and jointless nature of the seat 2 and the surrounding bead 3. While the seat and bead as well as the cap coöperating therewith are preferably circular, it will be understood that the same advantages will 10 result in differently shaping the structural features. The caps may be readily formed from refuse pieces of metal, thus further economizing in the attachment of a bail to a vessel.

15 The seats 2 are flat or do not partake of the convexity or rotundity of the body of the metallic vessel so that when the caps 4 are applied the edges thereof will contact fully with the said seats. The seats are 20 maintained in this flat condition when the body of the vessel is bent into desired form by the beads 3 which act to stiffen the portion of the body within their circumference and resist bending of the seats and insure a 25 preservation of a flat surface for the application of the edge of each cap. It is obvious that but for the beads surrounding the seats and offering a resistance to bending of the said seats, the latter would be given a convex 30 contour similar to the body of the vessel and make it very difficult to apply the caps. In point of fact, the semi-spherical cap or ear requires a flat surface to hold it successfully and in the preliminary preparation of 35 the sheet of metal from which the vessel body is formed, care will be taken in constructing the seats to preserve said seats in flat condition. By observing this important feature of construction, the plane constituting 40 the edges of the cap or ear meets a corresponding flat plane on the can body when the cap or ear is assembled with the body, and a much more perfect union results.

Having thus described the invention, 45 what is claimed as new, is:

1. The combination of a receptacle body having flat seats integrally formed there-

with by indenting the body from the exterior thereof inwardly at diametrically opposite points, the seats being surrounded by outer 50 beads, centrally perforated hemispherical caps having their circular edges applied within the beads and bearing against the outer surfaces of the seats, the caps having bail extremities loosely engaging the perforations thereof and terminally held therein, and securing means introduced in the beads around the caps.

2. A bail attaching means consisting of a vessel having a flat imperforate seat integrally formed therewith by indenting the body portion of the vessel from the exterior inwardly below the upper edge of the body and surrounded by a bead, a hollow cap having its edge fully applied to the seat, a 65 channel being formed between the edge portion of the cap and the bead and the cap centrally perforated to loosely receive a bail extremity which projects into the cap, and a securing means introduced in the said 70 channel.

3. A bail attaching means consisting of a vessel body having a flat seat integrally formed therein by indenting the body from the exterior thereof inwardly below the 75 upper edge of the said body, the seat having a bead surrounding the same and provided with an inner outwardly inclined wall, a hollow hemispherical cap having its circular edge fully engaging the seat within the bead 80 and forming an outwardly diverging channel with the bead, the said cap being centrally perforated to loosely receive a bail extremity, and solder introduced in the channel and forming a wedge shaped securing key for 85 the cap.

In testimony whereof I have hereunto set my hand in presence of two subscribing witnesses.

FREDERICK J. ENGLE.
